US0D1049805S

(12) **United States Design Patent** (10) **Patent No.:** **US D1,049,805 S**
(45) **Date of Patent:** **** Nov. 5, 2024**

(54) **CUTTING TOOL**

(71) Applicant: **Jameson, LLC**, Clover, SC (US)
(72) Inventors: **Carlos Becerra Alvarado**, Charlotte, NC (US); **Blake Tomlinson**, Statesville, NC (US)
(73) Assignee: **Jameson, LLC**, Clover, SC (US)

(**) Term: **15 Years**

(21) Appl. No.: **35/519,111**

(22) Filed: **Oct. 13, 2023**

(80) **Hague Agreement Data**

Int. Filing Date: **Oct. 13, 2023**

Int. Reg. No.: **DM/233142**

Int. Reg. Date: **Oct. 13, 2023**

Int. Reg. Pub. Date: **Nov. 24, 2023**

(51) **LOC (14) Cl.** **08-03**

(52) **U.S. Cl.**

USPC **D8/9**

Primary Examiner — Jack Reickel

Assistant Examiner — Michael A Kervin

(74) Attorney, Agent, or Firm — Shumaker, Loop & Kendrick, LLP; S. Alexander Long, Jr.

(57) **CLAIM**

The ornamental design for a cutting tool as shown and described.

DESCRIPTION

2.1 : Left

2.2 : Right

2.3 : Front

2.4 : Back

2.5 : Top

2.6 : Bottom

2.7 : Perspective

2.8 : Perspective

Matter shown in broken lines is not claimed and does not form part of the claimed designs.

1 Claim, 8 Drawing Sheets
